UNITED STATES PATENT OFFICE.

SAMUEL M. TEEETER AND CALVIN A. TEEETER, OF TUSCOLA, ILLINOIS.

HORSE-DETACHER.

SPECIFICATION forming part of Letters Patent No. 341,610, dated May 11, 1886.

Application filed March 22, 1886. Serial No. 196,107. (No model.)

To all whom it may concern:

Be it known that we, SAMUEL M. TEEETER and CALVIN A. TEEETER, of Tuscola, in the county of Douglas and State of Illinois, have 5 invented a new and useful Improvement in Horse-Detachers, of which the following is a specification, reference being had to the annexed drawings, forming a part thereof, in which—

10 Figure 1 is a side sectional elevation of one of the whiffletree-hooks employed as a part of our improved horse-detacher. Fig. 2 is a transverse section taken on line $x-x$ in Fig. 1. Fig. 3 is a plan view of a single-tree and a portion 15 of the double-tree, showing the devices for releasing the detacher.

Similar letters of reference indicate corresponding parts in the different figures of the drawings.

20 The object of our invention is to provide a simple, safe, and efficient device for releasing horses from vehicles in case of a runaway or accident.

Our invention consists in a whiffletree-hook 25 formed of two movable arms arranged to be held in position by a spring-acted bolt, which is withdrawn when it is desired to release the traces.

It also consists in an arrangement of cords 30 and levers for operating the spring-acted bolt from the carriage.

The ferrule A, which receives the end of the whiffletree, is provided in the outer end thereof with a recess, in which are pivoted two 35 arms, B C, on the pin D, extending transversely through the recess. The arm C is prolonged back of its pivot, extending outward to the outer surface of the ferrule A, thence along the side of the ferrule. The end of the extension of the arm C is beveled, and has a right-angled notch, a, which receives the notched end of a bolt, E, arranged to slide in the socket F, formed on the side of the ferrule A. The bolt is made in two diameters, and between 40 the shoulder b and the bottom of the socket the spring e is placed upon the bolt and arranged to push the bolt outward into engagement with the notched end of the arm C. The extremity of the bolt E passes through the 45 bottom of the socket F, and receives a cord or wire, d. The arm B is notched to receive a spiral spring, e, which abuts against the side

of the recess in the end of the ferrule, and tends to push the shoulder f, formed on the arm B, against the shoulder g on the arm C. 55 Normally the free ends of the arms B C are separated, as shown in the full lines in Fig. 1, and when it is desired to place the traces on the arms B C the arm B is moved forward toward the arm C, against the pressure of the 60 spring e, into the position indicated in dotted lines, when the trace may be readily put in place upon the arms B C, when the arm B, being released, springs away from the arm C and retains the trace in its place near the pivots of the arms. At or near the middle of the single-tree is pivoted an equal-armed lever, G, which receives in its opposite ends the cords or wires d on the bolts E at opposite ends of the single-tree. In the middle of the double-tree A are secured two eyes, h, which receive cords i from the levers G of the single-trees. The cords i, after passing through the eyes h, are connected with the cord j, which extends into the carriage within easy reach of 70 the driver. Normally the traces are held as indicated in Fig. 1, when the draft comes mainly upon the arm C; but when it is desirable to release the traces the cord j is pulled, the levers G are turned through the medium of the 75 cords i, thus drawing the cords d and withdrawing the bolts E from the notched ends of the arm C. The arm C, being released, is readily pulled by the traces into the position shown in dotted lines in Fig. 1, when, the arms 80 B C being parallel, the traces may readily slip from both arms.

Having thus described our invention, what we claim as new, and desire to secure by Letters Patent, is—

1. The combination with the ferrule A, having a recess in the end thereof, of the arm B, having the shoulder f, the spring e, the arm C, prolonged beyond its pivot, extending to the bolt E, and provided with the shoulder 90 g, the bolt E, and means for withdrawing the bolt E from the arm C, substantially as herein shown and described.

2. In a horse-detacher, the combination of the ferrule A, provided with an end recess, 100 the arm C, pivoted in the recess of the ferrule, prolonged beyond its pivot, and provided with the shoulder g, the arm B, pivoted in the recess of the ferrule and provided with the shoul-

der *f*, the spiral spring *e*, and means for holding and releasing the arm *C*, substantially as herein shown and described.

3. In a horse-detacher, the combination of 5 the ferrule *A*, the pivoted arm *C*, provided with the shoulder *g* and prolonged beyond its pivot, the pivoted arm *B*, having the shoulder *f*, the spring *e*, the spring-acted bolt *E*, cord *d*, lever *G*, and means for operating the lever, 10 substantially as herein shown and described.

4. In a horse-detacher, the combination of the ferrule *A*, the pivoted arm *C*, provided

with the shoulder *g* and prolonged beyond its pivot, the pivoted arm *B*, having the shoulder *f*, the spring *e*, the spring-acted bolt *E*, cord 15 *d*, lever *G*, and means for operating the lever, the cords *i j*, and eyes *h*, substantially as herein shown and described.
